TOY TELEPHONE

Jay V. Zimmerman, Clayton, Mo.

Application January 20, 1954, Serial No. 28,606

Term of patent 14 years

(Cl. D34—15)

FIG. 1.

FIG. 2.

FIG. 3.

FIG. 4.

FIG. 5.

I claim:

The ornamental design for a toy telephone, substantially as shown.
